CLAIM

The ornamental design for a headstock cover for a lathe, as shown and described.

DESCRIPTION

FIG. 1 is a front orthogonal view of a headstock cover for a lathe showing my new design;

FIG. 2 is a right orthogonal view thereof;

FIG. 3 is a left orthogonal view thereof;

FIG. 4 is a top orthogonal view thereof;

FIG. 5 is a rear orthogonal view thereof;

FIG. 6 is a bottom orthogonal view thereof;

FIG. 7 is a left perspective view thereof;

FIG. 8 is a right perspective view thereof;

FIG. 9 is a bottom perspective view thereof; and,

FIG. 10 is a left perspective thereof, where the frame of a headstock cover is shown removed for clarity of disclosure.

1 Claim, 10 Drawing Sheets
